KERF-CUTTING MACHINE

Herman W. Driehaus, Cicero, Ill., assignor to
 Goodman Manufacturing Company, Chicago,
 Ill., a corporation of Illinois

Application October 8, 1934, Serial No. 747,342

27 Claims. (Cl. 262—28)

This invention relates to improvements in kerf-cutting machines of the so-called universal or combination type adapted to cut vertical or shearing kerfs in the mine wall and horizontal kerfs adjacent the mine roof or floor or at various intermediate positions with respect thereto, and has as its principal objects to provide a new and improved kerf-cutting machine of the class described constructed with a view towards increased efficiency and ease of operation, compactness, ruggedness, and adaptability to varying mining conditions.

My invention may be more clearly understood with reference to the accompanying drawings wherein:

Figure 1 is a top plan view of a mining machine having the features of my invention embodied therein;

Figure 2 is a side elevation of the embodiment of my invention shown in Figure 1 with the cutter bar positioned for cutting a horizontal kerf;

Figure 3 is a side elevation of the embodiment of my invention shown in Figure 1 with the cutter bar positioned for cutting a vertical or shearing kerf;

Figure 4 is an enlarged fragmentary plan view of the forward portion of the embodiment of my invention shown in Figure 1 with certain parts broken away and shown in horizontal section to more clearly show certain details thereof;

Figure 5 is an enlarged fragmentary vertical sectional view of the forward portion of the device shown in Figure 1 showing certain parts in substantially longitudinal section;

Figure 6 is a transverse sectional view taken substantially along line 6—6 of Figure 5; and

Figure 7 is an enlarged fragmentary sectional view taken substantially along line 7—7 of Figure 6.

Like reference characters refer to like parts throughout the various figures.

With reference now to the details shown in the drawings, the main elements of the embodiment of my invention illustrated are similar to those illustrated in prior applications, Serial No. 659,522, filed by William W. Sloane on March 3, 1933, which issued as Patent No. 2,027,456, January 14, 1936, and Serial No. 697,141, filed by me on November 8, 1933, which issued as Patent No. 2,006,855, July 2, 1935, so will only be described insofar as is necessary to clearly illustrate the novel features of my present invention. Said main elements include a main frame or wheeled truck 10 carried on track wheels 11, 11 having a turntable 12 mounted on the forward end thereof and

forming a support for a cutting element, generally indicated by reference character 13.

Said truck is adapted to be propelled about the mine for moving the machine from working place to working place, or for sumping a cutter bar 14 into the coal by means of a motor 15 mounted thereon and a suitable system of reduction gearing driven thereby, which will not herein be described in detail since it is no portion of my present invention. Said motor also serves as a means for turning the turntable 12 at either a high or low speed for positioning or feeding the cutter bar across the face of the coal in front of the track.

The cutting element 13 is supported on the turntable 12 for vertical movement with respect thereto on a pair of widely spaced parallel upstanding guides 16, 16. Said guides are trunnioned on said turntable for adjusting the angle of the cutter bar 14 with respect to the mine bottom and are also counterbalanced to counteract the effect of the overhanging forward end of said cutting element, and will not be shown or described in detail since they form no part of my present invention and are clearly described in my aforementioned prior application.

Said cutting element includes a motor 17 of an ordinary electrical type secured to the rearward end of an elevator frame 19. Said elevator frame is supported in the parallel-spaced vertical guides 16, 16 for vertical adjustment with respect to said turntable and has a cutter frame 20 extending forwardly therefrom and supported thereby for rotational movement with respect thereto about an axis extending longitudinally of the machine. Said cutter frame is provided with a pair of parallel-spaced gibbed guides 21, 21 adapted to be engaged by a pair of corresponding guides 22, 22 extending from a cutter head 23 for adjustably supporting said cutter head for movement towards and away from said cutter frame. Said cutter head is adjustably moved towards and away from said cutter frame by means of a screw 24 in a well-known manner. Said screw is transversely pivoted between projections 25, 25 extending from the forward end of said frame on a pin 26. Said screw in turn is threaded within an internally threaded sleeve 27 which sleeve is threaded within a hub 28 of a worm gear 29. Said worm gear is journaled within the forward portion of said cutter frame in a suitable manner and is driven from the motor 17 by a suitable gear train which will hereinafter be more fully described.

The cutter head 23 forms a pivotal support

- for a cutter bar supporting member 30 in a usual manner and said cutter bar supporting member forms a support for the cutter bar 14 which projects therefrom. Said cutter bar has a cutter chain 31 orbitally movable thereabout, which is driven from a cutter chain sprocket 33 secured to an internally splined sleeve 34. Said sleeve in turn is suitably journaled within the cutter bar supporting member 30 (see Figure 5).
- 10 The sprocket 33 is rotated for driving the cutter chain 31 about the cutter bar 14 by means of a splined shaft 35 slidably engaging the internally splined sleeve 34. Said shaft also slidably engages the splined hub of a bevel gear 36 journaled 15 within the cutter frame 20. Said bevel gear is driven by a bevel pinion 37 keyed on the forward end of a drive shaft 39 coaxial with the axis of rotation of said cutter frame. Said drive shaft extends longitudinally of the elevator 19 and is 20 driven from the forward end of the motor 17 by means of a suitable system of reduction gears, not herein shown in detail, but clearly shown and described in the aforementioned prior application of William W. Sloane.
- 25 With reference now in particular to Figure 4 and the drive connections from the shaft 39 to the operating parts of the cutting element 13, a pair of oppositely disposed bevel gears 40, 40 are driven from the shaft 39 through a gear train, 30 generally indicated by reference character 41. Said bevel gears are selectively connectible with a transversely extending shaft 43 for driving said shaft in reverse directions without reversal of the motor 17. Said transverse shaft is operatively 35 connected adjacent its ends through self-locking gearing (not shown) to a pair of parallel-spaced shafts 44, 44 for vertically moving the cutting element in the guides 16, 16 in a manner set forth in the aforementioned prior application of William W. Sloane.
- 40 Spur gears 45, 45 are oppositely rotated by the bevel gears 40, 40 and mesh with spur gears 46, 46 freely mounted on a transverse shaft 47. Said last-named spur gears are selectively connectible 45 with said shaft for rotating said shaft in opposite directions without reversal of the motor 17 by means of suitable friction clutches 48, 48 of a usual construction. A worm 49 is keyed on said shaft and meshes with and drives a worm gear 50 50 keyed on a sleeve 51 coaxial with the longitudinal shaft 39 and freely rotatable with respect thereto.
- The sleeve 51 forms a drive member for a gear train for rotating the cutter frame 20 about a longitudinal axis and for other gear trains for moving the cutter head 23 and cutter bar 14 towards or from said cutter frame or swinging said cutter bar about an axis perpendicular to said longitudinal axis at a feeding speed in the following manner:
- 55 A spur pinion 53 is freely mounted on the forward end of said sleeve and forms a sun gear of a planetary gear train. Said spur gear meshes with spur gears 54, 54 disposed on opposite sides of its center. Said spur gears are journaled on shafts 55, 55 supported in a cage 56. Said cage is operatively connected with the cutter frame 20 for 60 rotating said cutter frame in a manner which is clearly described in the aforementioned application of William W. Sloane. Said spur gears 65 mesh with an internal gear 57 keyed on the inside of a bearing portion 59 formed integral with and extending forwardly of the elevator frame 19. Said bearing portion 59 forms a bearing support for the cutter frame 20 which is held in engagement therewith by an annular ring 60 which is

secured to said cutter frame and engages a shoul- 5 dered rearward portion of said bearing member (see Figures 4, 5, and 7).

The spur pinion 53 has integrally formed clutch jaws 61, 61 extending rearwardly therefrom which 10 are adapted to be engaged by forwardly project- 15 ing clutch jaws 62, 62 extending forwardly from and formed integral with feather keys 63, 63 feathered on the sleeve 51. Said feather keys are secured adjacent their rearward ends to a clutch 20 collar 64 and are moved along the sleeve 51 to engage the clutch jaws 62, 62 with or disengage said clutch jaws from the clutch jaws 61 for se- 25 lectively driving the spur pinion 53 from the sleeve 51 by means of a system of levers operative- 30 ly connected with said clutch collar in a manner which will hereinafter be more fully described. It will thus be apparent that the cutter frame 20 may be rotated by the motor 17 about an axis extending longitudinally of the machine in re- 35 verse directions without reversal of said motor.

Suitable means are provided for holding said cutter frame in fixed relationship with respect to said elevator frame when adjusted for cutting shearing or horizontal kerfs. Said means, as 40 herein shown, comprises a plurality of toothed sections or racks 65, 65 secured to the rearward face of the retaining ring 60 at spaced intervals therealong. Said toothed sections are adapted to be engaged with a toothed member 66 carried in 45 a slot formed in a lug 67 extending upwardly from the elevator frame 19. Said member is engaged with or disengaged from said toothed segments by means of a hand lever 69 which actuates an eccentric 70 operatively connected with said 50 toothed member by means of a link 71.

The cutter bar 14 is swung about an axis per- 55 pendicular to said longitudinal axis or moved towards and from the cutter frame 20 by means of a spur gear 73 keyed on the sleeve 51 adjacent but rearwardly of the spur pinion 53. Said spur gear is provided with a plurality of slots extending therethrough, along the sleeve 51, to slidably receive the feather keys 63, 63 which carry the clutch jaws 62, 62 on the forward end thereof. Said 60 spur gear meshes with and drives a spur pinion 74 feathered on a longitudinally extending shaft 75. Said shaft is journaled adjacent its ends in the cutter frame 20 for slidable movement with respect thereto in a suitable manner and said 65 spur gear is held from longitudinal movement with respect to said shaft by means of a cage 76, a portion of which cage also forms a bearing support for said shaft (see Figures 4 and 5).

A worm 77 is journaled for coaxial rotation 70 with respect to the shaft 75 adjacent the forward end thereof. Said worm meshes with and drives a worm gear 79 keyed on a vertically disposed sleeve 80 which sleeve is journaled within the cutter frame 20 in a suitable manner. The lower end 75 of the sleeve 80 is splined and is adapted to receive a splined shaft 81 which slidably engages the splined hub of a worm 83 journaled on its hub in the cutter head 23 adjacent the forward end thereof. Said worm meshes with and drives 80 a worm gear 84 keyed on a transverse shaft 85. A self-locking worm 86 is keyed on said trans- 85 verse shaft and meshes with a self-locking worm gear segment 87 secured to the cutter bar sup- 90 port member 30 for swinging the cutter bar 14 95 at a feeding speed (see Figure 3).

The worm 77 is provided with rearwardly pro- 95 jecting clutch jaws 88, 88 adapted to be engaged by clutch jaws 89, 89 on a clutch member 90 keyed to the shaft 75. Said clutch member is 99

provided with oppositely disposed clutch jaws 91, 91 adapted to engage forwardly projecting clutch jaws 93, 93 formed integral with a worm 94. Said worm is journaled in the cutter frame 20 coaxial with the shaft 75 and meshes with the worm gear 29.

Thus, by longitudinal movement of the shaft 75 in one direction or another, either the worm 71 or the worm 94 may be driven thereby for respectively swinging the cutter bar 14 at a feeding speed or adjusting said cutter bar towards or from the cutter head 23 without reversal of the motor 17, reversal of said shaft being controlled by the hereinbefore mentioned gears 46, 46 and 15 clutches 42, 48 (see Figure 4).

Referring now to several other novel features of my invention which include the clutch shifting means for shifting the shaft 75 for driving either of the worm gears 71 or 94 therefrom through the clutch member 90, and the means for shifting the feathered keys 63 and interlocking said shifting mechanisms so the cutter bar cannot be swung about an axis perpendicular to its plane of swinging at the same time it is being rotated about an axis extending longitudinally of the machine, a clutch yoke 95 engages the rearward end of the shaft 75. Said clutch yoke is engaged by a clutch fork 96 pivoted intermediate its ends between rearward projections 97, 97 of the cage 76. The opposite end of said clutch fork is bifurcated and engages oppositely disposed pins 99, 99 extending from a shifting member 100. Said shifting member slidably engages the hub of the spur gear 73 adjacent one of its ends and is mounted on a clutch collar 101 adjacent its opposite end. Said shifting member is freely rotatable with respect to said clutch collar which is mounted on the sleeve 51. Said clutch collar is engaged by a clutch fork 103 mounted on 40 a rock shaft 104 pivoted in the bottom of the elevator frame 19 (see Figure 5).

An arm 105 is formed integral with and extends upwardly and forwardly from one prong of said clutch fork and has a link 106 pivotally connected 45 to its upper end. The opposite end of said link is pivotally connected to a lever arm 107 secured to a transverse rock shaft 108. Hand levers 109, 109 are provided on opposite ends of said rock shaft for actuating said shaft and shifting the 50 shifting member 100 for pivoting the clutch fork 96 and shifting the shaft 75 with respect to the cutter frame 20 and engaging the clutch member 90 with either of the worm gears 71 or 94 (see Figure 4).

55 The means for shifting the clutch collar 64 includes a clutch fork 110 engageable with the clutch collar 64 and pivoted on a rock shaft 111 carried in the bottom of the elevator frame 19. A bifurcated lever arm 112 is formed integral with 60 and extends upwardly from one prong of said clutch fork and engages opposite sides of an eccentric 113 on a transverse rock shaft 114 spaced from but adjacent and parallel with the rock shaft 108. Hand levers 115, 115 are provided on opposite ends of said rock shaft for operating 65 said rock shaft from either side of the machine.

Means are provided for interlocking the rock shafts 108 and 114 to prevent engagement of one clutch mechanism when the other clutch mechanism is engaged. Said means includes a flanged sector 116 secured to the rock shaft 108 and another flanged sector 117 secured to the rock shaft 114. Said flanged sectors are so arranged that the flanges thereof face each other. The flange 75 of the flanged sector 116 is provided with an

opening 118 intermediate the ends thereof which is adapted to permit the flange of the flanged sector 117 to pass therethrough upon operation of the rock shaft 114. When positioned, as shown in Figure 5, either of the clutch mechanisms may 5 be shifted. When the rock shaft 114 is pivoted, the flange of the sector 117 will pass through the opening 118 and lock the rock shaft 108 from movement. In a like manner, when the rock shaft 108 is rocked from the initial position shown 10 in Figure 5, the flange of the flanged sector 117 will engage the flange of the flanged sector 116 upon movement of the rock shaft 114 for locking said rock shaft from movement.

It will thus be seen that a novel and improved 15 system of clutch shifting mechanisms has been provided, wherein a plurality of clutches remote from each other may be shifted from adjacent positions and that a novel and simplified interlocking means has been provided for preventing 20 rotation of the cutter head 23 about a longitudinal axis while the cutter bar 14 is being adjusted towards or from said axis of rotation or while said cutter bar is being swung about an axis perpendicular thereto and vice versa.

While I have herein shown and described one form of my invention, I do not wish to be limited to the precise details of construction or arrangement of parts herein shown and described, excepting as specifically limited in the appended 30 claims.

I claim as my invention:

1. In an apparatus of the class described, a frame member, another frame member rotatably supported by said first-mentioned frame member, a cutting element supported for pivotal movement with respect to said second-mentioned frame member about an axis perpendicular to the axis of rotation of said second-mentioned frame, power operated means for rotatably moving said second-mentioned frame member including a rotatable driving member, a clutch for controlling operation of said driving member and a rock shaft for operating said clutch, a rotatable driving member mounted in said second-mentioned frame, a drive 45 connection between said first and second mentioned rotatable driving members, a drive connection from said second-mentioned rotatable driving member for swinging said cutting element and a clutch controlling selective operation of said 50 drive connection, said last-mentioned clutch including a shifting member coaxial with said first-mentioned driving member and a rock shaft for operating said shifting member, and an interlocking connection between both of said clutches including interengaging means on said rock shafts. 55

2. An apparatus in accordance with claim 1, wherein said interengaging means includes a sector on each of said rock shafts, one of which sectors has an opening therein adapted to receive 60 said other sector and permit movement of said sector with respect thereto and lock the sector having the opening therein from movement.

3. In an apparatus of the class described, a frame member, another frame member supported 65 by the first frame member for rotatable movement with respect thereto, a cutting element supported by said second frame member for pivotal movement with respect thereto about an axis perpendicular to the axis of rotation of said second 70 frame, power operated means for rotatably moving said second frame member including a rotatable driving member, a gear coaxial therewith, a clutch selectively connecting said gear with said rotatable driving member and a rock shaft for 75

- operating said clutch, a rotatable driving member journaled in said second frame, a driving connection between said first and second mentioned rotatable driving members, a gear coaxial with said second mentioned rotatable driving member, a drive connection from said gear for swinging said cutting element, a clutch for connecting said gear with said rotatable driving member, operating means for said last named 5 clutch including means for translationally moving said second named driving member with respect to said gear, said last named clutch operating means including a shifting member coaxial with said first named driving member, and an interlocking connection between both of said clutch 10 operating means.
4. In an apparatus of the class described, a frame member, another frame member supported by the first frame member for rotatable movement with respect thereto, a cutting element supported by said second frame member for pivotal movement with respect thereto about an axis perpendicular to the axis of rotation of said second frame, power operated means for rotatably moving said second frame member including a rotatable driving member, a gear coaxial therewith, a clutch selectively connecting said gear with said rotatable driving member and a rock shaft for operating said clutch, a rotatable driving member journaled in said second frame, a driving connection between said first and second mentioned rotatable driving members, a gear coaxial with said second mentioned rotatable driving member, a drive connection from said gear for swinging said cutting element, a clutch for connecting said gear with said rotatable driving member, operating means for said last named clutch including means for translationally moving said second named driving member with respect to said gear, said last named clutch means including a shifting member coaxial with said first named driving member and a rock shaft for operating said shifting member, and an interlocking connection between said clutches comprising a sector on one of said rock shafts and another sector on the other rock shaft, said sectors being so arranged that one may engage the other upon operation of one rock shaft and the attempted operation of the other rock shaft. 15
5. An apparatus in accordance with claim 4, wherein one sector has an opening therein to receive and permit movement of said other sector and lock the sector having the opening therein from movement. 20
6. In a mining machine, a frame member, another frame member supported by said first frame member for rotatable movement with respect thereto, a projecting cutter bar supported by said second frame member for pivotal movement with respect thereto about an axis disposed perpendicularly to said first mentioned axis and for movement towards and from said axis, power operated means for rotatably moving said second frame about said axis including a rotatable driving member, a gear coaxial therewith, a clutch selectively connecting said gear with said rotatable driving member and a rock shaft for operating said clutch, a rotatable driving member journaled in said second frame, a geared connection between said first and second mentioned rotatable driving members, a gear coaxial with said second mentioned rotatable driving member, a drive connection from said gear for moving said cutter bar towards or from said axis of 25 rotation of said second frame, a clutch for operating said shaft, operating means for said last named clutch including means for translationally moving said second named driving member with respect to said gear, said last named means including a shifting member coaxial with said first named driving member, and an interlocking connection between both of said clutch operating means to prevent the operation of one while the other is in an operative position. 30
7. A mining machine in accordance with claim 6, wherein a rock shaft is provided for translationally moving said second named driving member and shifting said second named clutch, wherein said rock shaft is parallel with and adjacent to said first named rock shaft and wherein the interlocking connection between said rock shafts comprises a sector on one of said rock shafts and a sector on said other rock shaft, said sectors being so arranged that one may engage the other upon operation of one rock shaft and the attempted operation of the other rock shaft. 35
8. In a track-mounted mining machine, a truck having a turntable thereon, cutting mechanism mounted on said turntable including a forwardly projecting frame member having a projecting chain-carrying cutter bar carried thereby for movement towards and away therefrom and for swinging movement about an axis perpendicular to the longitudinal axis thereof, power operated means for driving said cutter chain about said cutter bar and independently moving said cutter bar towards and away from said cutter frame or swinging said cutter bar about its axis of pivotal connection to said frame comprising a shaft extending longitudinally of said frame, a sleeve coaxial with said shaft and reversely driven therefrom without reversal of said shaft, a parallel shaft driven by said sleeve, a worm on said shaft, a drive connection from said worm to said cutter bar for moving said cutter bar towards and away from said cutter head, another worm on said parallel shaft, a drive connection from said worm to said cutter bar for swinging said cutter bar at a feeding speed, and means for operatively connecting said shaft with either of said worms comprising a clutch member on said shaft intermediate said worms and means for shifting said shaft for engaging said clutch member with either of said worms. 40
9. In a track-mounted mining machine adapted to cut vertical or horizontal kerfs in a mine wall, a truck, cutting mechanism mounted on and projecting forwardly of said truck including a frame member mounted thereon, a cutter frame carried by said frame member for rotational movement with respect thereto about a longitudinal axis, a cutter head movable towards and away from said cutter frame, a cutter bar connected with said cutter head for pivotal movement with respect thereto about an axis perpendicular to said longitudinal axis, a sleeve coaxial with the axis of pivotal movement of said cutter frame, means selectively connectible with said sleeve for rotating said cutter frame, 45 a shaft carried by said cutter frame parallel to said sleeve, a drive connection from said sleeve to said shaft, means coaxial with and selectively connectible with said shaft for moving said cutter bar towards and from said cutter frame, and other means coaxial with and selectively connectible with said shaft for swinging said cutter frame with respect to said cutter bar at a feeding speed. 50
10. In a track-mounted mining machine adapted to cut vertical or horizontal kerfs in a 55

- mine wall, a truck, cutting mechanism mounted on and projecting forwardly of said truck including a frame member mounted thereon, a cutter frame carried by said frame member for rotational movement with respect thereto about a longitudinal axis, a cutter head movable towards and away from said cutter frame, a cutter bar connected with said cutter head for pivotal movement with respect thereto about an axis perpendicular to said longitudinal axis, a sleeve coaxial with the axis of pivotal movement of said cutter frame, means selectively connectible with said sleeve for rotating said cutter frame, a shaft carried by said cutter frame and arranged parallel to said sleeve, a drive connection from said sleeve to said shaft, means coaxial with and selectively connectible with said shaft for moving said cutter bar towards and from said cutter frame, other means coaxial with and selectively connectible with said shaft for swinging said cutter frame with respect to said cutter bar at a feeding speed, and means for selectively connecting said adjusting or swinging means with said shaft comprising a clutch member secured to said shaft and engageable with either said adjusting or swinging means upon translational movement of said shaft in one direction or another.
11. A mining machine in accordance with claim 9, wherein the means for adjusting said cutter bar towards and from said cutter frame includes a worm coaxial with said shaft and adapted to be selectively connectible therewith and wherein the means for swinging said cutter bar at a feeding speed includes another worm coaxial with said shaft and adapted to be selectively connectible therewith.
12. A mining machine in accordance with claim 9, wherein the means for adjusting said cutter bar towards and from said cutter frame includes a worm coaxial with said shaft and adapted to be selectively connectible therewith, wherein the means for swinging said cutter bar at a feeding speed includes another worm coaxial with said shaft and adapted to be selectively connectible therewith, wherein said worms are journaled in said cutter frame, and wherein an extensible drive connection is provided from said last-named worm to said cutter bar for swinging said cutter bar at a feeding speed.
13. A mining machine in accordance with claim 9, wherein the means for adjusting said cutter bar towards and from said cutter frame includes a worm coaxial with said shaft and adapted to be selectively connectible therewith, wherein the means for swinging said cutter bar at a feeding speed includes another worm coaxial with said shaft and adapted to be selectively connectible therewith, wherein said worms are journaled in said cutter frame, and wherein an extensible self-locking drive connection is provided from said last-named worm to said cutter bar for swinging said cutter bar at a feeding speed.
14. In a mining machine, a frame member, a second frame member rotatable with respect to said first frame member about a longitudinal axis, a projecting cutter bar having a cutter chain movable thereabout carried for adjustment towards and away from said second frame member and for pivotal movement with respect thereto about an axis perpendicular to said longitudinal axis, a drive shaft coaxial with said longitudinal axis, a drive connection from the forward end of said shaft to said cutter chain, a sleeve coaxial with said drive shaft, a drive connection from said sleeve for moving said second frame about said longitudinal axis, and means for selectively connecting said sleeve with said drive connection including a clutch member coaxial with said sleeve and a rock shaft for operating said clutch member, a longitudinal shaft journaled in said second frame and disposed parallel to said sleeve and driven therefrom, a gear freely mounted on said shaft adjacent the forward portion thereof, drive connections from said gear for moving said cutter bar towards and from said second frame, another gear freely mounted on said shaft forwardly of said first-mentioned gear, drive connections from said gear for swinging said cutter bar at a feeding speed, means for selectively connecting either of said gears with said shaft comprising a clutch member interposed between said gears, and means for translationally moving said shaft with respect to said gears for engaging said clutch member with either of said gears including an operating member coaxial with said sleeve.
15. A mining machine in accordance with claim 14, wherein a rock shaft is provided for operating said operating member and wherein an interlocking connection is provided between said rock shaft and said first-named rock shaft.
16. A mining machine in accordance with claim 14, wherein a rock shaft is provided for operating said operating member, wherein an interlocking connection is provided between said rock shaft and said first-named rock shaft and wherein said interlocking connection includes a sector on said first-named rock shaft adapted to engage a sector on said second-named rock shaft.
17. A mining machine in accordance with claim 14, wherein a rock shaft is provided for operating said operating member, wherein an interlocking connection is provided between said rock shaft and said first-named rock shaft and wherein said interlocking connection includes a flanged sector on said first-named rock shaft and a flanged sector on said second-named rock shaft, the flanges of said sectors being adapted to engage each other when one clutch member is in an engaged position and it is attempted to operate the other clutch member.
18. A mining machine in accordance with claim 14, wherein a rock shaft is provided for operating said operating member, wherein an interlocking connection is provided between said rock shaft and said first-named rock shaft and wherein said interlocking connection includes a flanged sector on said first-named rock shaft and a flanged sector on said second-named rock shaft, the flanges of said sectors being adapted to engage each other when one clutch member is in an engaged position and it is attempted to operate the other clutch and the flange of said last-named sector having an opening in the center thereof to permit passage of the flange of said other sector therethrough when said last-mentioned clutch member is in an intermediate position between said gears.
19. In a mining machine, a frame member, another frame member supported by said first frame member for rotatable movement with respect thereto about an axis extending longitudinally thereof, a projecting cutter bar supported by said second frame member for pivotal movement with respect thereto about an axis disposed perpendicularly to said longitudinal axis, power operated means for rotatably moving said second frame member including a rotatable driving member, a gear coaxial therewith, a clutch selectively connecting said gear with said rotatable driving member, and a clutch fork and rock

- shaft for operating said clutch, a rotatable driving member journaled in said second frame, a geared connection between said first and second-mentioned rotatable driving members, a gear coaxial with said second-mentioned rotatable driving member, a drive connection from said gear for swinging said cutter bar at a feeding speed, a clutch for operatively connecting said gear with said shaft, operating means for said 5 last-named clutch including means for translationally moving said second-named driving member with respect to said gear operated by means closely adjacent the means for operating said first-named clutch means, said last-named 10 means including a shifting member coaxial with said first-named driving member, and an interlocking connection between both of said clutch operating means to prevent the operation of one while the other is in an operative position.

20 20. In a mining machine, a frame member, another frame member supported by said first frame member for rotatable movement with respect thereto about an axis extending longitudinally thereof, a projecting cutter bar supported 25 by said second frame member for pivotal movement with respect thereto about an axis disposed perpendicularly to said longitudinal axis, power operated means for rotatably moving said second frame member including a rotatable 30 driving member, a gear coaxial therewith, a clutch selectively connecting said gear with said rotatable driving member, and a clutch fork and rock shaft for operating said clutch, a rotatable driving member journaled in said second frame, a geared connection between said first and second-mentioned rotatable driving members, a gear coaxial with said second-mentioned rotatable driving member, a drive connection from said gear for swinging said cutter bar at a 35 feeding speed, a clutch for operatively connecting said gear with said shaft, operating means for actuating said last-named clutch including means for translationally moving said second-named driving member with respect to said gear operated by means closely adjacent the means 40 for operating said first-named clutch means, said means including a rock shaft parallel to said first-mentioned rock shaft, and a shifting member coaxial with said first-named driving member and moved with respect thereto by said rock 45 shaft, and an interlocking connection between said rock shafts to prevent the operation of one while the clutch operated by the other is in an engaged position.

50 55. 21. A mining machine in accordance with claim 20, in which the interlocking connection between the rock shafts comprises a sector on one of the rock shafts and another sector on the other rock shaft, and wherein said sectors are 55 so arranged that one may engage the other upon operation of one rock shaft and the attempted operation of the other rock shaft.

60 65. 22. In a mining machine, a frame member, a second frame member rotatable with respect to said first frame member about a longitudinal axis, a projecting cutter bar having a cutter chain movable thereabout carried for adjustment towards and away from said second frame member and for pivotal movement with respect thereto about an axis perpendicular to said longitudinal axis, a drive shaft coaxial with said longitudinal axis, a drive connection from the forward end of said shaft to said cutter chain, a sleeve coaxial with said drive shaft, a drive connection from said sleeve for moving said second 70 frame about said longitudinal axis, and means for selectively connecting said sleeve with said drive connection including a clutch member coaxial with said sleeve and a rock shaft for operating said clutch member, a longitudinal shaft parallel to said sleeve and driven therefrom journaled in said second frame, a drive connection from said parallel shaft for adjustably moving said cutter bar towards and from said second frame including a worm coaxial with said shaft, and selectively connectible therewith, a worm gear driven thereby and a threaded shaft secured to said cutter bar adjacent the longitudinal center thereof and operatively connected with said worm gear, another drive connection from said shaft for swinging said cutter bar at a feeding speed including a worm coaxial with said shaft and selectively connectible therewith, a worm gear driven thereby, and an extensible self-locking drive connection from said worm gear to said cutter bar including a splined shaft slidably movable with respect to said worm, a worm driven by said splined shaft and a geared connection from said worm to said cutter bar.

75 80. 23. In a mining machine, a frame member, a second frame member rotatable with respect to said first frame member about a longitudinal axis, a projecting cutter bar having a cutter chain movable thereabout carried for adjustment towards and away from said second frame member and for pivotal movement with respect thereto about an axis perpendicular to said longitudinal axis, a drive shaft coaxial with said longitudinal axis, a drive connection from the forward end of said shaft to said cutter chain, a sleeve coaxial with said drive shaft, a drive connection from said sleeve for moving said second frame about said longitudinal axis, and means for selectively connecting said sleeve with said drive connection including a clutch member coaxial with said sleeve and a rock shaft for operating said clutch member, a longitudinal shaft parallel to said sleeve and driven therefrom journaled in said second frame, a drive connection from said parallel shaft for adjustably moving said cutter bar towards and from said second frame including a worm coaxial with said shaft and selectively connectible therewith, a worm gear driven thereby and a threaded shaft secured to said cutter bar adjacent the longitudinal center thereof and operatively connected with said worm gear, another drive connection from said shaft for swinging said cutter bar at a feeding speed including a worm coaxial with said shaft and selectively connectible therewith, and means for selectively connecting either of said worms with said shaft comprising means for translationally moving said shaft in one direction or another.

85 90. 24. A mining machine in accordance with claim 23, wherein the means for translationally moving the parallel longitudinal shaft in one direction or another for selectively connecting either of the worms with said shaft includes a shifting member coaxial with the axis of rotation of said second frame member and an operative connection from said shifting member to said parallel longitudinal shaft.

95 100. 25. A mining machine in accordance with claim 23, wherein the means for translationally moving the parallel longitudinal shaft in one direction or another for selectively connecting either of the worms with said shaft includes a shifting member coaxial with the axis of rotation of said second frame member, an operative connection from said shifting member to said parallel longitudinal shaft.

gitudinal shaft and a rock shaft for operating said shifting member, and wherein means are provided for interlocking the rock shaft for operating the clutch means for controlling movement 5 of the second frame about a longitudinal axis with said rock shaft for shifting said longitudinal shaft which comprise a sector on one of said rock shafts, and a sector on the other of said rock shafts adapted to engage or be engaged 10 by said first-mentioned sector depending upon which rock shaft is being operated.

26. A mining machine in accordance with claim 23, wherein the means for translationally moving the parallel longitudinal shaft in one direction or another for selectively connecting either of the worms with said shaft includes a shifting member coaxial with the axis of rotation of the second frame member, an operative connection from said shifting member to said shaft 15 and a rock shaft for operating said shifting member, and wherein means are provided for interlocking said rock shaft for operating the clutch means for controlling movement of the second frame about a longitudinal axis with said rock shaft for shifting said longitudinal shaft, which comprise a flanged 20 sector on one of said rock shafts, and a flanged sector on the other of said rock shafts, the flange of one of said flanged sectors having an opening in the central portion thereof to receive the flange of said other flanged sector and lock said last- 25 named flanged sector from movement.

either of said rock shafts have been moved, and one of said sectors having an opening therein to receive and permit movement of said other sector and lock said sector having the opening therein from movement.

27. A mining machine in accordance with claim 23, wherein the means for translationally moving the parallel longitudinal shaft in one direction or another for selectively connecting either of the worms with said shaft includes a shifting member coaxial with the axis of rotation of the second frame member, an operative connection from said shifting member to said parallel longitudinal shaft and a rock shaft for operating said shifting member, and wherein means are provided for interlocking the rock shaft for operating the clutch means for controlling movement of the second frame about a longitudinal axis with said rock shaft for shifting said longitudinal shaft, which comprise a flanged 20 sector on one of said rock shafts, and a flanged sector on the other of said rock shafts, the flange of one of said flanged sectors having an opening in the central portion thereof to receive the flange of said other flanged sector and lock said last- 25 named flanged sector from movement.

HERMAN W. DRIEHAUS.
